GUN SWIVEL

John L. Cline, Portland, Oreg.

Application August 1, 1949, Serial No. 107,956

1 Claim. (Cl. 42—85)

1

This invention relates generally to the art of gun making and particularly to a gun swivel.

The main object of this invention is to provide a gun swivel which will be easy to attach and release from a gun stock and in which the swivelling action is limited in order to prevent the strap from becoming twisted.

I accomplish this and other objects in the manner set forth in the following specification as illustrated in the accompanying drawing, in which:

Fig. 1 is a side elevation of a rifle showing the position of the swivel.

Fig. 2 is a fragmentary section along the line 2—2 in Fig. 1.

Fig. 3 is a section through the device, showing it attached to the stock, the section being taken along the longitudinal axis of the gun.

Fig. 4 is a section taken along the line 4—4 in Fig. 3.

Fig. 5 is similar to Fig. 4, but showing the retracted position of the retaining balls.

Fig. 6 is a plan view of the nut used for the manner of attaching shown in Fig. 2.

Like numbers of reference refer to the same or similar parts throughout the several views.

Referring in detail to the drawing, there is shown a common form of rifle 10 having a stock 11 and grip 12, to the opposite ends of which it is desired to secure a gun strap 13.

Referring particularly to my invention, same will be seen to consist of a sleeve 14 having a closed end 15 and occupying a recess 16 in the stock 11. A flat headed wood screw 17 passes through the end 15 into the stock 11. Within the open end of the sleeve 14 is formed a raceway 18.

A plug 19 is provided having a reduced end 20 which is slidable and rotatable within the sleeve 14. The reduced portion 20 has mounted there-in a plurality of balls 21 which are radially movable and rotatable in the holes 22 which are slightly inclined with relation to the axis of the plug 19.

Within the plug 19 is formed an axial bore 23, 45 whose outer end 24 is counter-bored and whose end 25 is closed.

Within the bore 23 is placed a spring 26 which bears against the closed end 25. Within the bore 23 is a plunger 27, whose head 28 is slidable within the counter-bore 24. The plunger 27 has a

2

raceway 29 formed therein, within which the balls 21 normally travel when the swivel is to be separated; that is, when the plug 19 is to be withdrawn from the sleeve 14.

5 Beyond the raceway 29 is a third raceway 30 which engages the balls 21 under the pressure of the spring 26.

In order to limit the rotation of the plug 19 with relation to the sleeve 14, I have provided an 10 indent 31 which normally engages the balls 21 and prevents their rotation beyond the limit of said indent 31.

A strap ring 32 is provided for the plug 19 and it is of a shape common to such devices now in 15 use.

In the form of the device shown in Fig. 2, which is exactly the same as the one shown in Fig. 3, the sleeve 14 is held in place by a machine screw 33 which extends into the nut 34 which 20 clears the rifle barrel 10.

It can be seen from the foregoing that the device constructed, as thus far described, will permit the plug 19 to rotate with the balls 21 riding in the raceway 30.

25 In order to limit this rotation, the indent 31, which is disposed between a pair of the balls 21, thereby limiting the rotation of the plug 19 to less than 240°.

I claim:

30 A gun swivel comprising a sleeve adapted to be recessed into a gun stock, said sleeve having a raceway formed therein, an indent in said sleeve extending into said raceway, a plug rotatably mounted in said sleeve, said plug having radial 35 holes formed in the side thereof inclined with relation to the axis of the plug, a ball disposed in each of said holes, a plunger disposed along the axis of said plug having a pair of raceways formed around same of unequal depth, a spring within 40 said sleeve urging said plunger outwardly in a manner to urge its shallower raceway against said balls and force same outwardly through said holes into the raceway in said sleeve.

JOHN L. CLINE.
